UNITED STATES PATENT OFFICE.

ERNEST K. HOOD, WILLIAM J. CAMPBELL, AND CHESTER BRADFORD, OF INDIANAPOLIS,
INDIANA.

SPECIFIC-GRAVITY GRADING APPARATUS.

1,175,763.

Specification of Letters Patent. Patented Mar. 14, 1916.

Application filed March 29, 1909. Serial No. 486,527.

To all whom it may concern:

Be it known that we, ERNEST K. HOOD, WILLIAM J. CAMPBELL, and CHESTER BRADFORD, citizens of the United States, residing at Indianapolis, in the county of Marion and State of Indiana, have invented certain new and useful Improvements in Specific-Gravity Grading Apparatus, of which the following is a specification.

10 In preparing peas for packing it is highly desirable to separate them into grades as respects quality. This can be done by delivering them into a tank containing a fluid of the proper specific gravity, such as brine, 15 in which the harder and heavier peas will sink, while the softer and lighter ones will float.

Our object is to provide a convenient and efficient mechanism for separating the two 20 grades of peas or other goods of different specific gravities in such a tank.

An apparatus embodying our present invention is illustrated in the accompanying drawings, in which—

25 Figure 1 is a perspective view of an apparatus of the character in question; Fig. 2 a front elevation thereof; Fig. 3 a top or plan view; Fig. 4 a side elevation, the side of the tank however being broken away to show the 30 mechanism therein; Fig. 5 a side elevation, on an enlarged scale, of so much of the apparatus as includes the shorter of the two elevators and immediately adjacent parts; Fig. 6 a view partially in side elevation and 35 partially in central section of one of the elevator buckets, and fragments of the elevator chains and guiding track therefor; Fig. 7 an end elevation also partly in section of one of said buckets; Fig. 8 a detail 40 horizontal sectional view as seen when looking downwardly from the broken line 8 8 in Fig. 9; Fig. 9 a detail vertical sectional view as seen when looking in the direction indicated by the arrows from the broken 45 line 9 9 in Fig. 10; Fig. 10 a view as seen when looking in the direction indicated by the arrows from the broken lines 10 10 in Figs. 8 and 9; Fig. 11 a detail sectional view of the guiding track coupling, similar to a 50 portion of Fig. 10 but on a larger scale; Fig. 12 a detail plan view of a fragment of one of the arms carrying the propelling blades or wings; Fig. 13 a fragmentary elevation of

the same, and Fig. 14 a fragmentary detail similar to a portion of Fig. 4 but on an enlarged scale.

The tank 21 is in greater part substantially a vertically-positioned cylinder, having a closed bottom 22 and an open upper end, and is of a size sufficient to handle the required amount of peas being treated. We consider a convenient size to be about seven feet in diameter and five feet in height. At one side, this tank is continued beyond the cylinder outline to provide gathering spaces into which the separated peas are conducted, and from whence they are removed by the two elevating systems provided for the purposes, as will be presently more fully described. Above the bottom 22 of the tank is an inclined perforate false bottom 23, down which the peas which sink through the brine will roll to a point adjacent to the lower end of the longer of the two elevators. The upper edge of this false bottom is secured to the peripheral wall of the tank, at a point just below the revolving wings (presently to be described) and tapers thence toward the position occupied by the bottom of said longer elevator—the tapering being thus both from the rear of the tank toward the front, and from the side of the tank occupied by the short elevator toward the side occupied by the long elevator. The upper edge of this false bottom is carried by a ledge 20 (preferably formed of angle iron) secured to the internal surface of the wall of the tank 21, and suitable supporting bars 24 run therefrom at the proper inclination across the tank to its bottom at or near the point at which the heavy peas are to be delivered. If any dirt gets into the brine with the peas, it will pass through the perforations in this false bottom, and can then be drawn off through a blow-off pipe 25 by opening its valve 26. Just at the place where the long elevator comes there is a depression or pocket formed, and from the bottom of this a second and smaller blow-off pipe 27 is placed having a valve 28. Directly below the revolving wings, we place, within the tank, and extending transversely thereto, a central partition 29, the purpose of which is to prevent the body of brine from acquiring a whirling motion. Said partition extends from just below the revolving wings to just

above the false bottom—a small space being left below the partition over the false bottom to enable the peas which reach that point on the higher side to pass on through 5 to the lower side on their way to the long elevator.

At the top of the tank 21 is a shaft 31 mounted in appropriate bearings carried by cross timbers 32. At one end this shaft bears 10 a pulley 33, the hub of which has a clutch face 34 which is adapted to engage with a corresponding face on a clutch member 35 secured on the shaft. A shifting lever 33' is provided to throw pulley 33 into and out 15 of engagement. The driving belt B (from an appropriate source of power,—not shown) runs to this pulley 33 and drives the apparatus.

Centrally within the tank is a vertical 20 shaft 41 bearing upon its upper end a beveled gear wheel 42 with which a bevel pinion 43 on shaft 31 engages, and whereby said vertical shaft 41 is given a rotary motion. Near the upper end of shaft 41, but slightly 25 below the upper edge of the tank, we secure radial arms which extend nearly to the inner peripheral wall of the tank, which arms are composed of suitable bars 44 carrying perforate blades or wings which extend to 30 below the surface of the brine in the tank; and, as shaft 41 is revolved, serve to drive around in front of them, whatever peas are floating upon the surface of the brine. These blades, as shown in Figs. 3, 4, 11 and 35 12, are preferably formed in sections, and the separate sections are pivotally attached to the arms. In detail, the blade sections consist of frames 45 having perforate bodies 46 (preferably of screen wire) and the upper 40 edges of the frames have attached thereto pivots 47, which are preferably screw threaded and provided with wing-nuts 48 in order that the blades may be positioned as desired. The series of blades on a single arm may all 45 be controlled, if desired, by a single rod 49 extending substantially parallel with the arm 44. We have shown as a means of connection between this rod and the several blades a slideable coupling 49' engaging with 50 a stud 45' on frame 45 of the wing. The coupling 49' is held to desired position on rod 49 by means of a clamp screw s. By this means, not only may the parts be easily connected together, but the couplings 49' 55 and rod 49 may be so adjusted in relation to each other as to cause the various blades or wings to set at varying angles if desired, and thus get exactly the direction of force in the movement of the floating peas at 60 all stages which is desired. We have also (see especially Fig. 3) shown the outer end of arm 44 with a reverse curve, thus bringing the end of the blade more squarely against the goods in operation at this point. 65 The brine will of course to a large extent

pass back through the perforations in the blades, while the peas will be forced along in front thereof. The peas will however escape from one set of blades to the space behind it (through the openings left between the several blades) in the arrangement shown; and this, will enable us to cause the peas to move as slowly as desired from the center toward the circumference of the tank. If the blades were made continuous, it would of course drive the peas out toward the periphery of the tank considerably more rapidly. By the arrangement shown and thus described we are enabled to control this matter with great accuracy to 75 produce exactly the results sought. When the peas have finally reached the position at the outer ends of the arms close to the peripheral wall of the tank, they will escape therefrom and pass through an opening formed 80 in said peripheral wall near its upper edge just in front of the short elevator. The momentum which they have acquired will cause them to float over the buckets of said elevator, by which they will be caught and 85 thence conveyed away out of the tank. 90

On the opposite end of shaft 31 from pulley 33 is a sprocket wheel 36, from which a sprocket chain 37 runs to a sprocket wheel 38 on the end of the main elevator shaft, 95 whereby said shaft and the elevators are driven. This main elevator shaft 51 is mounted in suitable bearings carried by frame 52 and bears four sprocket wheels 53, 54, 55 and 56. A second shaft 57 arranged 100 parallel with shaft 51 bears four other corresponding sprocket wheels 58, 59, 60 and 61. To this extent, the two elevators are uniform. A short shaft 62, positioned a short distance below the surface of the brine in the 105 tank and there carried by suitable bearings, carries two other sprocket wheels 63 and 64 for the bottom of the short elevator. Another short shaft 65 carries still two other sprocket wheels 66 and 67 over which the 110 chains of the short elevator run, and which are so arranged as to provide the necessary return from extreme position. The two boxes 68 and 69 to this last mentioned shaft are adjustable, and thus serve as means to 115 adjust the tension of the short elevator chains. Chains 71 and 72 of this short elevator run over the sprocket wheels described, and carry the elevating buckets 73, which buckets are composed of perforated 120 or reticulated material, as shown, and which receive and elevate the peas which are delivered in proper relation thereto by the operation of the revolving wings or blades in the tank. These elevating buckets are attached to the chains by means of pivots p formed on appropriate links of the chains and which enter corresponding perforations in arms 75 on said buckets. The arms 75 are 125 crank-arms in form (as best shown in Fig. 130

4) and, at their opposite ends, where they are attached to the buckets, pass between the sides of guiding tracks, and are thus caused to travel in the required direction as will 5 now be described.

The guiding tracks are each composed of two continuous bars 81 and 82, between which the necks of the crank-arms 75 pass, and said guiding tracks are so arranged in 10 relation to the chains as to hold the elevating buckets in upright position while elevating, and also while passing along transversely at the top of the elevator; but, as best shown in Fig. 5, when said buckets 15 reach the outer end of the elevator, near the point where they are to start on the return trip, they begin to turn over, and, by the time that they have reached a position just below the sprocket wheels 55 and 56, 20 they have turned completely upside down, so as to discharge their contents into whatever receptacle is provided for the purpose below them at that point. By this peculiar arrangement in attaching the buckets to the 25 traveling sprocket chains and controlling their movement by means of the peculiarly formed guiding track, we are enabled to secure the very desirable result of absolutely controlling the position of the buckets 30 throughout the entire distance, thus securing that they shall be in upright position during the portion of the travel when that is desired, and shall reverse the position, and thus fully and completely discharge 35 their contents, at the precise point desired. There is another advantage incident to the means which we have shown and described for attaching the buckets to the elevator chains. If the buckets were attached rigidly to the chains, the tendency would be, as 40 the buckets traveled through the brine, to push the goods away from the bucket; while, with the pivoted and crank-arm-guide attachment which we have provided, and the 45 relative positioning of the guide tracks, the bucket is always so positioned and guided as to dip under and skim up the goods efficiently. That is, when the bucket is advancing toward the goods, its open upper 50 side or mouth is so presented as to cause the goods to enter it easily.

The long elevator is the same in construction and arrangement as the short elevator, it simply being of greater length, so that it 55 extends to the bottom of the tank and into the pocket there provided in order to receive and elevate the harder peas which have sunk through the brine. The shafts 51 and 57 serve for both elevators, and the 60 sprocket wheels thereon have already been enumerated. At the bottom of the long elevator is a shaft 91 (corresponding to shaft 62 of the short elevator) bearing sprockets 92 and 93; and near the top (substantially in line with shaft 65, and cor-

responding therewith) is another short shaft 94 bearing sprockets 95 and 96. The elevating chains and buckets which run over these various sprocket wheels, and the guiding tracks by which the position of the buckets is controlled are identical, except in length, with those of the short elevator, and, therefore, will not be further described. The bearings 97 and 98 for the lower short shaft 91 are, however, mounted upon detachable supporting frames which, upon occasion, may be raised to the top of or out of the tank, for purposes of renewal, adjustment or repair of any of the submerged elevator parts without the necessity of drawing off the liquid contents of the tank. These detachable supporting frames are illustrated in Figs. 8, 9 and 10. As best illustrated in Fig. 9, there are two of these frames, one upon each side of the elevator 80 shaft or space. These frames consist of distance bars 101 extending from the top of the tank to near the bottom, upon the lower ends of which the boxes or bearings 97 and 98 are secured. At the upper portion of 85 the tank, and at the top of the bar 101, (which is shown as an angle iron) is a U-shaped bar 102 connected by means of bolts 103 to the adjacent wall of the tank. Struts 104 extend out from the bar 102 and carry 90 the adjacent portions of the guiding tracks 181 and 182 (corresponding to the bars 81 and 82 of the short elevator hereinbefore described) at that point. Near the lower end of bar 101 is another U-shaped bar 105, 100 which carries struts 106, to the projecting ends of which the guiding tracks 181 and 182 are also secured. The U-shaped bar 105, instead of being bolted to the wall of the tank, rests in brackets 107 secured to 105 the wall of the tank. As shown, the upper sides of these brackets are open, so that when the structure is unfastened at the top, it may be lifted out free from said brackets without difficulty. The guiding tracks 181 and 182 are shown as separable just above the top edge of the tank, where coupling plates 111 and 112 are shown as secured thereto by means of bolts 113 and 114. As 110 is obvious, in order to separate these guiding tracks at this point, it is only necessary to loosen the bolts and remove the coupling plates, as is best shown in Figs. 10 and 11. Making this part of the apparatus removable and replaceable is of considerable advantage in case of any disarrangement or breakage of the submerged elevator mechanism, as thereby we are enabled to perform the work of readjustment or repair without discharging and consequently losing the 115 brine or grading liquid.

The operation of this apparatus may be recapitulated as follows: The peas (or other articles to be graded) are introduced 120 into the tank, preferably at about the point 125

marked 100 in Fig. 3. The tank has previously been filled with a fluid (commonly brine) of a specific gravity intermediate that of the articles to be separated or graded. That is, the specific gravity of the brine is greater than that of the lighter articles, but less than that of the heavier articles. Upon being introduced into the tank, the heavier articles will sink (either 10 quickly or slowly according to whether the differences between the specific gravities is great or small), while the articles which are of less specific gravity than the fluid will float thereon. The perforated blades or 15 wings, slowly revolving through the upper portion of the fluid contents of the tank, will push the floating articles before them, until they are finally delivered through the upper opening in the peripheral wall of 20 the tank to a point adjacent to the short elevator, whence they will be taken by said short elevator and carried away and delivered into such receptacle as may be provided for the purpose. Those articles which 25 sink will slide or roll down the inclined false bottom of the tank, and finally reach a position at the bottom of the long elevator, whence they will be carried by said elevator in a similar manner as the lighter articles, and delivered, separately, into such 30 receptacle as may be provided therefor.

It will be noticed that the openings in the peripheral wall of the upright cylindrical tank are substantially tangential. That is, 35 the upper opening through which the articles which float pass to the shorter elevator is tangential to the upper portion of the tank, while the opening through which the articles which sink pass to the longer elevator is substantially tangential to the lower portion of the tank. By this arrangement, we are enabled to place the two elevators side by side, which is a matter of considerable advantage, both in economy of construction, and in convenience. As will be 40 obvious, however, one of these elevators might be arranged tangential of the tank on one side, and the other on the other, without departing from our invention.

Having thus fully described our said invention, what we claim as new, and desire to secure by Letters Patent, is,

1. The combination, in a specific gravity grading apparatus, of a vertically-positioned cylindrical tank containing the grading fluid provided with discharge openings in its peripheral wall, an adjacent inclosure within which elevators may be placed, means for delivering the articles to be separated through said openings, and elevators arranged adjacent to said openings to receive and elevate the separated articles.

2. The combination, in a specific gravity grading apparatus, of a tank containing the 65 grading fluid provided with upper and

lower discharge openings in its peripheral wall, means consisting of a vertical shaft provided with wings for delivering the articles to be separated which float to the upper discharge opening, other means for delivering the articles which sink to the other discharge opening, and elevators arranged adjacent to said discharge openings to receive and elevate the separated articles.

3. The combination, in a specific gravity grading apparatus, of a vertically-positioned cylindrical tank containing the grading fluid provided with discharge openings, one at the upper portion of the tank and one at the lower portion thereof, an adjacent inclosure into which the lower ends of elevators extend, means for delivering the articles to be separated through said discharge openings, and elevators the lower ends whereof are arranged adjacent to said discharge openings to receive and elevate the separated articles.

4. The combination, in a specific gravity grading apparatus, of a tank containing the grading fluid, elevators associated therewith, means consisting of a vertical shaft provided with wings for delivering the articles to be separated to one of said elevators, and other means consisting of an inclined false bottom of the tank for delivering the 95 articles which sink to the other elevator.

5. The combination, in a specific gravity grading apparatus, of a vertically-positioned cylindrical tank containing the grading fluid and provided with discharge openings in its peripheral wall, means consisting of a vertical shaft provided with wings for delivering the articles to be separated which float to the upper discharge opening, other means for delivering the articles which sink to the other discharge opening, a partition extending transversely of the tank below the revolving wings for retarding the current which might otherwise be caused by said wings, and elevators associated with said tank arranged to receive and elevate the separated articles.

6. The combination, in a specific gravity grading apparatus, of a vertically-positioned cylindrical tank containing the grading fluid, a central shaft arranged vertically therein, wings carried by said shaft for moving the floating articles, an inclined bottom for guiding the articles which sink to a predetermined point, and two elevators associated with said tank, one leading from the point to which the floating articles are delivered by the wings and the other leading from the point to which the sinking articles are delivered by the inclined bottom.

7. The combination, in a specific gravity grading apparatus, of a tank, a central vertical shaft therein, arms on said shaft, and wings carried by said arms for moving the floating articles, said wings being adjust-

able to vary the positions thereof, whereby the delivery of the floating articles may be adjustably controlled.

8. The combination, in a specific gravity grading apparatus, of a tank, a central vertical shaft therein, arms on said shaft, wings formed in sections with each section adjustably mounted on an arm, and means for adjusting said wings.

10 9. The combination, in a specific gravity grading apparatus, of a tank, a central vertical shaft therein, arms on said shaft, wings formed in sections with each section adjustably mounted on an arm, and means for adjusting said wings, said means including devices whereby the adjustment may be effected either individually or collectively.

10 10. The combination, in a specific gravity grading apparatus, of a tank, a central vertical shaft therein, arms on said shaft, wings formed in sections with each section adjustably mounted on an arm, means for adjusting said wings, and a shifting rod adjustably connected to said wings whereby they may be adjusted simultaneously.

11. The combination, in a specific gravity grading apparatus, of a tank, a central vertical shaft therein, arms on said shaft, wings formed in sections with each section adjustably mounted on an arm, means for adjusting said wings, and a shifting rod adjustably connected to said wings whereby they may be adjusted simultaneously, the connections between the wings and the shifting rod being also adjustable whereby variations between the respective wings as well as adjustability of position may be attained.

12. The combination, in a specific gravity grading apparatus, of a tank, means for separating the articles to be graded therein, elevators associated with said tank for receiving the several grades of separated articles, the lower section of that elevator which extends to near the bottom of the tank being separable and removable, whereby access may be had thereto for purposes of readjustment or repair without discharging the liquid from the tank.

13. The combination, in a specific gravity grading apparatus, of a vertically positioned cylindrical tank containing the grading fluid and provided with discharge openings in its peripheral wall, means for delivering the separated articles through said openings, elevators arranged beyond said openings to receive and elevate the separated articles, one of said elevators extending to just below the surface of the grading fluid and another extending to near the bottom of the tank, the frame structure of the latter elevator being separable at a point above the level of the grading fluid, whereby the lower portion may be removed without discharging said grading fluid.

In witness whereof, we have hereunto set our hands and seals at Indianapolis, Indiana, this twenty-third day of March, A. D. one thousand nine hundred and nine.
